UNITED STATES PATENT OFFICE.

MARTIN L. UNGER, OF NELSON, NEBRASKA, ASSIGNOR OF ONE-HALF TO
JACOB RITTERBUSH, OF SAME PLACE.

CAR-COUPING.

SPECIFICATION forming part of Letters Patent No. 405,285, dated June 18, 1889.

Application filed February 5, 1889. Serial No. 298,755. (No model.)

To all whom it may concern:

Be it known that I, MARTIN L. UNGER, a citizen of the United States, residing at Nelson, in the county of Nuckolls and State of 5 Nebraska, have invented new and useful Improvements in Car-Couplings, of which the following is a specification.

My invention relates to improvements in car-couplings; and it consists in certain novel 10 features hereinafter described and claimed.

In the accompanying drawings, Figure 1 is a perspective view of a car-coupling constructed in accordance with my invention. Fig. 2 is a longitudinal vertical section, and Fig. 3 is a 15 transverse vertical section of the draw-head.

Referring to the drawings by letter, A designates the end of the car, and B the draw-head, secured thereto in the usual manner. The draw-head is hollow, and is provided with 20 an interior transverse partition C, and in its side walls, at the top and bottom of the same, has the longitudinal grooves D, as shown. From the upper side of the draw-head, at the front end of the same, a stop E depends into 25 the path of the sliding block.

F designates the sliding block, provided on its sides with the longitudinal ribs G, which engage the grooves D, and having a recess G in its front end to receive the end of the link. 30 From the rear end of this sliding block a stem or rod H projects through the transverse partition C in the draw-head, and around this stem, between the rear end of the sliding block and the transverse partition, a spring I 35 is coiled, so as to bear against the sliding block and force it normally toward the front end of the draw-head.

On the upper side of the draw-head, at the front end of the same, I provide the vertical 40 frame J, having a pulley K journaled in its upper end and having a horizontal stop-plate secured below said pulley. The coupling-pin M moves in this frame, and is adapted to pass through suitable pin-holes in the top and bottom of the draw-head. The coupling-pin is 45 provided at its upper end with a cross-head N, which is adapted to contact with the upper side of the draw-head and thereby limit the downward movement of the coupling-pin.

A chain or cable O is secured to the upper 50 end of the coupling-pin, and extends upward over the pulley K and then rearward to a rotary rod on the end of the car.

P designates the rotary rod, which is mounted vertically on the ends of the car, and 55 has the end of the cable O secured to its lower portion. A spring Q is secured to the end of the car and wrapped around the said rod, so that after the said rod has been operated to raise the coupling-pin the spring will return 60 it to its initial position in order to allow the coupling-pin to fall. R designates a pulley mounted on the top of the car at the end of the same, and S is a cable secured to the rod P and passing over said pulley. The cable S 65 passes along the top of the car to the opposite end of the same, and a shorter cable T is connected thereto and extends down the side of the car.

When the parts are uncoupled, the sliding 70 block will be at the front end of the draw-head and the coupling-pin will be resting thereon. When the cars are to be coupled, the link is secured in one draw-head and the two cars then brought together. As the link enters the stationery draw-head, it will contact with the sliding block to push the same backward, allowing the coupling-pin to fall by gravity into engagement with the link. The cars are 75 uncoupled by rotating the rod P, so as to raise 80 the coupling-pin, thereby allowing the coupling-link to be released from the draw-head. The device can be uncoupled from the top or side of the car and from either end.

From the foregoing description it will be 85 seen that I have provided a very compactly-arranged and simple car-coupling, which is very efficient in operation. The recess in the front end of the sliding block holds the link in its proper position. The longitudinal ribs 90 on the sliding block and the grooves in the draw-head give the sliding block a positive movement, so that the proper operation of the device is insured. The frame in which the coupling-pin works protects the said pin 95 against injury, and also guides it in its movements, so that it will always engage the link when lowered.

Having thus described my invention, what I claim, and desire to secure by Letters Patent, is—

1. The combination of the draw-head, the 5 vertical frame erected thereon, the transverse roller in the upper end of the frame, the coupling-pin moving in the vertical frame and having a cross-head N bearing against the sides of the vertical frame, the vertical rotary rod 10 arranged in rear of the vertical frame, and the cable secured to the coupling-pin, passing over the roller and connected to the rotary rod, as set forth.

2. The combination, with the car and the 15 draw-head, of the rotary rod mounted on the

car, the spring secured to the car and wrapped around the said rod, the pulley on the upper side of the car, the cable secured to the rod and passing around the pulley, the vertical frame on the draw-head, the coupling-pin 20 moving in said frame, and the cable connecting the pin with the rotary rod, as set forth.

In testimony that I claim the foregoing as my own I have hereto affixed my signature in presence of two witnesses.

MARTIN L. UNGER.
